US00D783421S

(12) **United States Design Patent** (10) **Patent No.:** **US D783,421 S**
Van Belle et al. (45) **Date of Patent:** **** Apr. 11, 2017**

(54) **SEEDLING TRAY**

(71) Applicant: **Van Belle Nursery Inc.**, Abbotsford (CA)

(72) Inventors: **William David Van Belle**, Abbotsford (CA); **Diego Fernando Martinez Manay**, Abbotsford (CA)

(73) Assignee: **Van Belle Nursery Inc.**, Abbotsford (CA)

(**) Term: **15 Years**

(21) Appl. No.: **29/550,629**

(22) Filed: **Jan. 5, 2016**

(51) LOC (10) Cl. **09-03**

(52) U.S. Cl.

USPC **D9/760**

(58) **Field of Classification Search**

USPC D9/762, 757, 737, 761, 420-426, 432, D9/418, 415, 501, 72, 739, 742, 753, 756, D9/741; D7/611, 550.1, 605, 701, 553.1, D7/553.2, 614; D3/313, 304, 311, 314, D3/315; D6/396, 397, 449, 450, 466, D6/469, 629; D24/227; 206/139, 206/201-203, 427, 265, 504, 518, 519, 206/524.1, 557, 561, 564, 565, 703, 704, 206/705, 523, 586, 515, 521.1, 521.15, 206/521.3, 521.6, 521.8, 521.4, 521.9, 206/406; 220/4.26, 508; 229/406; 426/119, 112, 298, 614; D11/143, 155, D11/156

(57) **CLAIM**

The ornamental design for a seedling tray, as shown and described.

DESCRIPTION

FIG. 1 is a top perspective view of a seedling tray showing the design;

FIG. 2 is a bottom perspective view thereof;

(Continued)

FIG. 3 is a top view thereof;
 FIG. 4 is a bottom view thereof;
 FIG. 5 is a side view thereof; and,
 FIG. 6 is an end view thereof.
